UNITED STATES PATENT OFFICE.

LEON BENOIT, OF CHICAGO, ILLINOIS.

MACHINE FOR ASSEMBLING CARTONS.

Application filed March 21, 1927. Serial No. 176,945.

This invention relates to a machine for assembling loose partitions in a carton such, for example, as is suitable for the reception of eggs. A carton of the general type for which the present machine is adapted is set forth in the Coyle Patent No. 1,327,946, of January 13, 1920, this being merely a suggestive construction in this connection.

The carton herein set forth consists of a blank which is doubled over along its longitudinal center and which is provided in each of its two sections with registering transverse slots through which are inserted loose partition members. As these partitions are several in number for each carton, it follows that the operation of setting these partitions in place involves considerable time and effort. It is with a view to expediting this assembly of the partitions in such a carton that the present machine has been designed.

An exemplification of the present invention is set forth in the accompanying drawings in the manner following:

Figure 1 is a vertical section through a table or bench whereon is mounted the present machine which is shown in elevation;

Fig. 2 is a horizontal section therethrough on line 2-2 of Fig. 1;

Fig. 3 is a detail in perspective of the gauge which centers the carton blank in position for reception of the partitions;

Fig. 4 is a side elevation of the machine looking toward the side opposite from that which appears in Fig. 1;

Fig. 5 is a front elevation of the machine;

Fig. 6 is a vertical section therethrough taken on line 6-6 of Fig. 2 looking in the direction of the arrows;

Fig. 7 which is a view similar to Fig. 2 shows the parts moved to advance the partition through the carton blank;

Fig. 8 is a detail of certain of the parts shown in Fig. 7, and shows the carton blank laterally shifted after insertion of the partitions therein;

Fig. 9 is a perspective view showing the carton blank with the partitions assembled therein; and

Fig. 10 is a transverse section through the carton fully set up with the cross partitions forming individual pockets for the reception of eggs or other commodities.

The carton blank herein shown is doubled upon itself as at 11, preferably along its longitudinal center, so as to provide adja-

cent sections through which are formed a plurality of registering slots 12 transversely disposed. Each of these slots terminates short of the folded edge 11 when the material may be slightly cut away to provide recesses 13 which are aligned with the slots. With a carton blank so constructed partitions B are assembled, one for each slot. As shown, each partition is in the form of a card having a generally rectangular shape with a central slot 14 extending inwardly from one edge. For a portion of its length one of the walls defining this slot is obliquely disposed as at 15. The opposite slot wall 16 continues straight until close to the card edge where an offset is provided in the form of a protruding lug 16.

The machine which assembles the partition cards within the slots of the carton blank will now be explained. As shown in Fig. 1, it may be mounted upon a bench or table 20 with which is associated a pivotal support 21 for a lever 22 constituting an operating treadle. Pivoted as at 23 to the treadle is a second lever 24 having a laterally extending pedal 25 adapted, when depressed, to engage with the proximate end of the treadle lever 22 whereby to move the same. A spring connection 26 extending between the treadle 22 and the table 20 normally holds the former in an upward position, and by means of a similar spring connection 27, which extends upwardly from the pedal lever 24, this latter element also is normally maintained in an upper position.

The upper end of the spring connection 27 is joined to a bell crank 28 pivoted as at 29 to a fixed part of the machine. A link connection 30 also extends between the upper end of the treadle lever 22 and a pusher bar 31 slidably mounted within bearings 32 to reciprocate certain parts within the machine. As by means of adjustable stops 33 the movement range of the pusher bar can be definitely controlled. The effect of pressure applied to the pedal 25 is first to transmit movement to the bell crank lever 28, following which the treadle 22 is actuated to reciprocate the pusher bar 31.

A vertically extending head 35 connected to one end of the pusher bar is slidably mounted within the machine frame which includes a vertical wall 36. I provide also upon the pusher head a series of bracket supports 37 spaced equidistantly one above the other. These supports each afford a mount-

ing for a blade 38 which extends laterally of the pusher head and through slots 39 in the frame wall 36. Each blade at its outer end may be bent upon itself as at 40 so as to embrace loosely one edge of a guide plate 41 carried between respective front and rear walls 42 and 43 which are supported adjacent the ends of the frame wall 36. The front wall is, by preference, not quite perpendicular to the line of movement of the pusher rod 31 and ejecting blades 38 carried thereby.

Upon the side of the machine opposite to that shown in Fig. 1 are certain compartments which are defined by the several guide plates 41. Preferably a swinging frame affording a partial closure for these compartments is also provided and for this purpose I have shown two vertical bars 45 in spaced relation having their ends supported in upper and lower arms 46 and 47 respectively, each having a pivotal mounting as at 48 upon a fixed part of the machine frame. Upon each of the guide plates may be stacked a quantity of partition members B, a weight plate 49 being rested upon each stack, if desired. By closing the swinging frame which consists of the vertical bars 45, these several stacks of cards are held against accidental displacement.

Adjacent one side of the front of the machine is a vertically extending shaft 50 the ends of which are rotatively carried within upper and lower bearings 51. Mounted on the shaft near its lower end is a pinion 52 in meshing relation with a rack bar 53. This rack bar is extended rearwardly along one side of the machine, as indicated in Fig. 1, for connection with a spring 54 which tends to draw the bar rearwardly. Extending laterally from the shaft 50 are a plurality of bars 55 one for each card stack on the guide plates 41. The swinging ends of these bars may be connected to a common vertical bar 56. These several bars form, in effect, a gate which is normally held open, as shown in Figs. 1 and 2 by the spring 54. This gate is adapted to be closed, however, in response to movement of the bell crank 50 transmitted through a connection consisting of a slot 57 and pin 58 therein extended laterally from the rack bar. It will accordingly be noted that actuation of the pedal 25 acts to bring about an immediate closing of the gate preliminary to transmission of any motion to the pusher bar 31.

A carton blank which is folded once upon itself, as shown in Figs. 7 and 8, may be brought to operative position against a pair of stops 60 which center the work horizontally. The vertical positioning of the blank is assured by means of a single gauge which, as shown best in Fig. 3, may comprise a thin blade 61 extended laterally from an arm 62 which is carried upon the end plate 42 in

line with one of the slots 63 therein through which the partition members are projected. With the work so positioned, pressure is thereupon applied to the pedal 25 which (1) swings the gate around to hold the work against the plate 42, and (2) projects a plurality of partition members in unison, one through each of the several slots 12 which are formed in the carton blank. As viewed in plan, the gate bars 55 are slightly bent as at 65 to provide work engaging points which are relatively close to the transverse middle of each partition member. If desired the front wall 42 may be equipped with rest plates 66 slightly bent or recessed in conformity with the bars of the gate, whereby the carton blank is permitted to flex inwardly near its middle at such time as the partition members are to be inserted therein. With advance of the partition members, one corner of each will first enter a slot of the carton blank which initially is aligned with the end plate 42. After the partitions have been advanced to their limit, the blank is then shifted laterally, as viewed in Fig. 8, and swung around into alignment with the central slot 14 of the partitions, and by reason of this blank movement all the partitions are then interlocked with the blank at one extreme end of the slots 12.

The advantages of the present machine are that it facilitates assembly of the partition members into the carton blank. Were this operation to be performed by hand, it would be necessary to handle each of these partitions separately. With the present machine, however, all the partition members are correctly positioned in one operation. This is accomplished expeditiously and always with a uniformity which is sparing of damage to the carton.

I claim:

1. A carton assembling machine in which is combined means for centering a slotted carton in position to be operated upon, ejectors for moving simultaneously a plurality of partitions, one into each slot of the carton, and a single operating means for holding the carton in place and for causing advance of said ejectors, substantially as described.

2. A carton assembling machine in which is combined means for centering a slotted carton adjacent one edge of a partition member adapted to be inserted therethrough, means for advancing the partition into the carton slot, means for holding the carton stationary during such movement, and a single operating means for the two means last mentioned, substantially as described.

3. A carton assembling machine in which is combined a plurality of ejectors each arranged to displace the lowermost of a plurality of superposed stacked partition mem-

- bers, means for holding a carton blank in position for insertion through slots therein of said partition members, said means permitting a lateral movement of the carton blank after the partition members are inserted therein, and means for operating said ejectors simultaneously, substantially as described.
4. In a carton assembling machine, the combination of a plurality of ejectors adapted to advance a plurality of partitions, means for holding a carton blank in position for insertion through slots therein of said partitions, the blank being disposed angularly with respect to the line of advance thereof, said holding means permitting the carton blank thereafter to be shifted laterally and be straightened up perpendicularly to the line of partition advancement, and means for operating said partition ejectors simultaneously, substantially as described.
5. In a carton assembling machine, the combination with a frame, of a head slidably mounted therein, means for reciprocating the head, a plurality of ejectors connected for movement with the head and extended laterally therefrom through the frame, guide plates, one for each ejector, providing supports for a plurality of stacked partitions the lowermost of which is displaceable with each forward movement of the ejectors, and means for holding a slotted carton blank in position to receive therethrough a plurality of partitions with a single operation of the ejector head, substantially as described.
6. In a carton assembling machine, the combination of a rest for a slotted carton blank, an ejector adapted to insert a slotted partition through the carton, means for arresting movement of the ejector when the partition and carton slots are in register, and a single means operating sequentially to press the carton blank against the rest and to actuate the ejector, substantially as described.
7. In a carton assembling machine, the combination of a reciprocable head, a frame wherein the head is slidably mounted, a plurality of horizontal ejector blades movable with the head, a guide plate associated with each blade and providing a support for a stack of slotted cards, means for centering a slotted carton blank adjacent the several stacks with the slots in the blank registering with the lowermost card in each stack, and means for advancing the head together with its blades whereby to move the lowermost card through the proximate slot in the carton blank, substantially as described.
8. In a carton assembling machine, the combination with means for holding a slotted carton blank in a predetermined position in which it is laterally shiftable, of means for inserting a slotted card through the blank, and means for arresting such insertion when the carton and card slots are in register to permit the carton to be then shifted laterally whereby the card is interlocked therewith, substantially as described.
9. In a carton assembling machine, the combination of a reciprocable ejector adapted to advance a slotted card, a rest adjacent the carton edge against which a slotted carton blank may be placed to receive insertion of the card therethrough, the rest being disposed out of perpendicular relation to the line of advance of the ejector, and means for centering the carton against the rest, said means permitting the carton to be shifted laterally of the rest and to be straightened into perpendicular relation with the line of movement of the ejector, substantially as described.
10. In a carton assembling machine, the combination of a vertical frame wall having horizontal slots therein, a head slidably mounted on one side of said wall, ejector blades carried by the head and extended laterally through said slots to the opposite side of said wall, supports on said latter side of the wall whereon are arranged a plurality of card stacks one in operative relation to each ejector blade whereby the lowermost card in each stack may be displaced thereby, a movable closure for holding all of said stacks in position, and means for retaining a slotted carton blank in position to receive simultaneous insertion of a card from each stack substantially as described.

LEON BENOIT.
